UNITED STATES PATENT OFFICE.

CLARENCE G. PERKINS, OF MUNCIE, INDIANA.

DESIGN FOR PIERCING IMPLEMENT.

Application filed June 17, 1927. Serial No. 22,468. Term of patent 3½ years.

To all whom it may concern:

Be it known that I, CLARENCE G. PERKINS, a citizen of the United States, residing at Muncie, in the county of Delaware and State of Indiana, have invented a new, original, and ornamental Design for Piercing Implements, of which the following is a specification, reference being had to the accompanying drawing, forming a part hereof.

Figure 1 is a perspective view and Figure

2 is a top plan view of a piercing implement, showing my new design.

The object of the article in which my new design is shown is to pierce a hole in a tin can, also to break through the appropriate places in a can or the like.

I claim:

The ornamental design for a piercing implement, as shown and described.

CLARENCE G. PERKINS.
